UNITED STATES PATENT OFFICE

IRA J. McCULLOUGH, OF HUNTINGTON PARK, CALIFORNIA

JARRING TOOL

Application filed March 18, 1930. Serial No. 436,735.

This invention relates to a well tool and relates more particularly to a jarring tool adapted to be used in a well during fishing operations, and the like.

Various forms of tools have been suggested and employed in fishing operations to impart a jarring action to parts or tools within a well. The usual or common forms of jarring tools include sections, connected for limited 10 relative longitudinal movement, that are normally held against movement in a contracted position and include means which suddenly release the sections for movement to cause a violent jarring or hammering action between 15 shoulders or suitably designed parts on the sections. In the usual forms of jarring tools the loosely connected sections are released, to cause the jarring action, by rotating the operating member or string or by varying the 20 pressure on the circulation fluid passed by the operating member. It is not always desirable or practical to rotate the operating string to actuate a jarring tool or to vary the pressure on the circulation fluid to operate such a 25 tool. Further, the types of jarring tools operated by rotation embody parts that are subjected to severe strains and which soon become worn and inoperative.

It is a general object of the present invention to provide a jarring tool for use in a well that may be operated without rotating the operating member or without varying the pressure on the fluid in the operating member. The tool provided by the present invention 30 is operable by simple reciprocation of the operating member.

It is another object of the invention to provide a jarring tool of simple, sturdy construction that is effective and dependable of operation.

It is another object of the invention to provide a jarring tool of the character mentioned that embodies sections related for relative longitudinal movement, latches for releasably holding the sections in a contracted position, and a control for the latches whereby the latches are released upon a predetermined strain being imparted to the sections. The control for the latches is a feature of the 40 invention and operates by yieldingly resisting

a tensile strain on the sections to cause the release of the latches upon a predetermined strain being imparted to the tool.

Another object of the invention is to provide a jarring tool of the character mentioned 55 that does not embody the common forms of springs for resisting the strains imparted to the tool and to provide a tool which may be operated without interfering with the circulation of fluid.

Other objects and features of my invention will be best and more fully understood from the following detailed description of a typical form and application of the invention throughout which description reference is 60 had to the accompanying drawings, in which:

Fig. 1 is a longitudinal detailed sectional view of the tool provided by this invention illustrating it in the contracted or unactuated position. Fig. 2 is a view similar to Fig. 1 70 illustrating the parts in the actuated position. Fig. 3 is an enlarged longitudinal detailed sectional view of the central portion of the tool illustrating the parts in a partially 75 operated position. Figs. 4, 5, and 6 are enlarged detailed transverse sectional views taken as indicated by lines 4—4, 5—5, and 6—6 on Fig. 1, respectively.

The broader features of the present invention are capable of embodiment in various 80 forms of tools and in various arrangements and combinations of parts. Throughout the following detailed description I will describe the invention embodied in a simple form of jarring tool adapted to be used with the 85 equipment employed in the rotary method of well boring and which is intended primarily to be employed in fishing operations, or the like, to impart a jarring action to loosen or release an object in a well.

The jarring tool which embodies the present invention includes, generally, two sections A and B connected or related for limited relative longitudinal movement and adapted to be connected between an operating string and the part to be jarred, latch means 10 for releasably holding the sections A and B in a contracted position against relative movement, and yieldable control means 11 whereby the latches are released 95 100

upon a predetermined strain being imparted to the sections A and B.

The sections A and B, which are the body or main elements of the tool, constitute an assembly adapted to be connected between the object to be jarred and an operating string. The sections A and B may be connected between parts of an operating member if desired. The body sections A and B are connected for relative longitudinal movement. In the preferred form of the invention the sections A and B are telescoped, that is, one section extends into or is arranged within the other. In the particular case illustrated in the drawings the section A is the upper section and is tubular and the section B is the lower section and extends into the section A. In this form of the invention the section A is adapted to be connected with an operating member or operating string, while the section B is adapted to be connected with the object to be jarred. It will be obvious that the lower section, that is, the section B may be made tubular to receive the upper section A without departing from the broader principles of the present invention.

The section A of the tool is the upper or outer section and encases the various principal parts of the tool. The body section A is an elongated tubular member and may be constructed in various manners. In the particular form of the invention illustrated the outer section A is formed of two simple parts, a main or body part 12, and a head or upper part 13. The body part 12 of the section A may be a simple elongated tubular part. The upper part 13 may be screw threaded into the upper end of the body part 12 and may be provided at its upper end with a screw threaded pin 14 to facilitate connection with an operating member such as a string of drill pipe, or the like. The upper part 13 is provided with a central longitudinal opening 15 which communicates with the interior of the body part 12. The body part 12 may be of uniform diameter throughout its length. An inwardly projecting annular flange 16 is provided on the interior of the body part 12 of the section A. The flange 16 may be provided at or adjacent the lower end of the body part 12. The upper end of the flange 16 provides an upwardly facing shoulder 17 which is adapted to cooperate with a shoulder on the section B to provide the jarring or hammering action when the latch means 10 is released as will be herein-after described.

The section B, which is the lower and inner section of the particular form of tool being described, is adapted to be connected with the object to be jarred or with a part of an operating string or member. The section B is an elongated part in the form of a stem which extends upwardly into the interior of the section A. The section B may include a

lower portion 18 and an upper portion 19. The lower portion 18 of the section B projects into the lower end of the body part 12 of the section A and is slidable in the opening 20 through the flange 16. The lower portion 18 projects downwardly from the lower end of the section A and the downwardly projecting portion may be provided with any suitable means for connection or attachment with a fishing tool or other part. A collar 21 is screw threaded on the portion 18 below the lower end of the section A. The upper end of the collar 21 is adapted to cooperate with the lower end of the body part 12 of the section A to limit the relative longitudinal movement of the sections A and B in one direction.

The portion 18 is provided with keys or splines 22 slidable in longitudinal keyways or grooves in the opening 20 to connect the sections A and B against relative rotation. The portion 18 is provided with a head or enlargement 23 which is slidable on the interior of the part 12 of the section A. The lower end of the enlargement 23 provides a downwardly facing shoulder 24 which is adapted to cooperate with the shoulder 17 upon releasing of the latch means 10. With the parts in the contracted or unactuated position such as is shown in Fig. 1 of the drawings, the shoulder 24 is spaced from the shoulder 17. The shoulder 24 is adapted to engage the shoulder 17 to limit the relative longitudinal movement of the sections A and B in one direction while the collar 21 is adapted to engage the lower end of the section A to limit the relative movement of the sections in the other direction.

The upper portion 19 of the section B is an elongated part which projects or extends a considerable distance through the section A. The lower end of the upper portion 19 may be screw threaded into a socket 25 in the upper end of the portion 18. The upper end of the portion 19 extends into and is slidable in the opening 15. The portion 19 of the section B is of considerably less diameter than the interior of the part 12 of the section A so that an annular space is provided between the portion 19 and the interior of the part 12.

The latch means 10 is provided to releasably hold the sections A and B of the tool against relative longitudinal movement when in the contracted or unactuated position. The latch means 10 includes a latch or latches 27 connected with one of the sections A or B through the yielding means 11 and adapted to cooperate with a part or shoulder on the other section to releasably hold the two sections against relative longitudinal movement. The latches 27 may be connected with either of the sections A or B through the means 11 to cooperate with the other section. In the particular case illustrated the latches 27 are connected with the section A through

the means 11 to cooperate with a shoulder 30 on the section B to releasably hold the sections A and B against relative longitudinal movement. The latches 27 are shiftably mounted within the section A.

5 The latches 27 may be supported on a carrier 31 shiftably mounted in the annular space between the upper part 18 of the section B and the interior of the part 12 of the section A. The carrier is mounted above the 10 upper end of the lower portion 18 of the section B. The carrier 31 may be an annular member slidably guided on the inner walls of the part 12 of the section A. The carrier 31 is provided with a central opening 32 freely 15 passing the upper portion 19 of the section B. There may be any desired number of latches 27 supported on the carrier 31. The latches 27 are pivotally connected with the carrier and are adapted to act under compression 20 when engaging the shoulder 30 to releasably hold the section A and B against relative movement. The lower ends of the latches 27 seat in recesses 33 in the upper portion of the carrier 31. In the particular form of 25 the invention illustrated there are three latches 27 equally spaced about the central longitudinal axis of the tool. The lower ends of the latches 27 are pivotally mounted in the recesses 33 by pivot pins 34 extending transversely through the recesses 33 and through openings in the lower portions of the latches 27. The latches 27 project upwardly from the carrier 31 and their upper portions or 30 ends are adapted to cooperate with or engage the annular shoulder 30 on the section B. The shoulder 30 is provided on the portion 19 of the section B above the carrier 31 when it is in the normal or unactuated position. The shoulder 30 may be provided by the lower 35 end of a replaceable bearing ring 36 screw threaded on the portion 19. The upper end of the ring 36 may seat against a downwardly facing shoulder 37 on the portion 19. The shoulder 30 and the upper ends of the latches 27 are formed so that the latches readily slide 40 from or operate off the shoulder when permitted to release through the yielding of the means 11. In the case illustrated the shoulder 30 is beveled upwardly and outwardly and the upper ends of the latches 27 are provided 45 with correspondingly shaped faces 38 to seat against the shoulder 30. The latch carrier 31 is supported by or connected with the section A through the yielding means 11 and 50 normally carries the latches 27 so that they are in cooperative engagement with the shoulder 30 and act under compression between the shoulder and the carrier 31 to releasably hold the sections A and B against relative 55 longitudinal movement.

In accordance with the invention means is provided for holding the latches 27 in cooperative engagement with the shoulder 30 until the tool has been subjected to a pre-

determined tensile strain and the means 11 has yielded a certain amount. A sleeve 40 is slackly or loosely connected with the body part 12 of the section A to normally retain the faces 38 of the latches 27 against the shoulder 30. The sleeve 40 is slidably arranged within the part 12 above the upper ends of the latches 27. The sleeve 40 may be slideable on the exterior of the portion 19 of the section B. The sleeve 40 is mounted within the part 12 for limited longitudinal movement relative to the section A and accordingly relative to the section B. A part in the form of a screw 41 projects inwardly from the interior of the part 12 of the section A and extends into a longitudinal groove 42 on the exterior of the sleeve 40 to prevent rotation of the sleeve and to limit the movement of the sleeve 40 relative to the section A. The lower end of the sleeve 40 normally extends over the upper end parts of the latches 27 to retain the latches in cooperative engagement with the shoulder 30. In the particular case illustrated the latches 27 have upper parts which normally seat in recesses 43 in the lower end of the sleeve 40. The sleeve 40 is carried by the section A so that the upper ends of the latches 27 extend into the recesses 43 and are in cooperative engagement with the shoulder 30 when the parts are in the normal or unactuated position. Upon relative movement of the sections A and B through yielding of the means 11 the screw 41 causes the sleeve 40 to move with the section A and upon the means 11 yielding a predetermined extent the sleeve 40 is shifted out of engagement with the upper ends of the latches 27 so that the latches 27 are free to operate off the shoulder 30.

In the preferred form of the invention means is provided for returning the latches 27 to their normal positions in engagement with the shoulder 30 after actuation. In the particular case illustrated leaf springs 44 project from the carrier 31 and engage the outer sides of the latches 27 to urge the upper ends of the latches inwardly.

The yielding means 11 is in the nature of a control for the latch means 10 and is operable to cause the release of the latches 27 from the shoulder 30 through yielding a certain extent to a predetermined tensile strain. The means 11 connects the carrier 31 with the section A of the tool. The means 11 includes one or more yieldable members 50 connecting the carrier 31 with the section A. The members 50 are extensible or capable of elongation and are resilient so that they contract or return to their normal size or length after actuation. In accordance with this form of invention the members 50 are in the form of cables. The members 50 may be formed of stranded cable having the desired characteristics or

capabilities. There may be any suitable number of members 50 connecting the carrier 30 with the section A, the number of members 50 depending upon their qualities of resistance and resiliency. In the case 5 illustrated I have shown three equally spaced members 50 connecting the carrier 31 with a sub block 51 arranged adjacent the upper end of the part 12 of the section A.

10 The block 51 may be screw threaded in the part 12 and may have a central opening 52 slidably passing the portion 19 of the section B. The upper ends of the members 50 may be connected with the block 51 in any suitable manner, while the lower ends of the members 50 may be secured to the carrier 31 by any suitable means. In the form of the invention illustrated the upper end portions of the members 50 extend 15 through openings 53 in the sub block 51. An enlargement or head 54 is provided on the upper end of each member 50 to seat against the upper end of the block 51 to prevent the displacement of the members 50 from the openings 53. The lower end portions of the members 50 may extend through openings 55 in the carrier 31. The extreme 20 lower portions of the members 50 may be wedged into the openings 55 to be securely connected to the carrier 31. The members 50 are preferably made comparatively long so that they will have the desired range of extension without being weakened or fractured through the tensile strain imparted 25 on the tool.

It is preferred to provide means for circulating fluid through the tool. In the form 30 of the invention illustrated a central longitudinal opening 60 extends completely through the section B of the tool from one end to the other. The upper end of the opening 60 communicates with the opening 15 of the part 13 of section A, while the lower end of the opening 60 may discharge into the tool 35 or part attached to the lower end of the section B. In the preferred form of the invention grooves 70 are provided in the opening 20 through the flange 16 to permit the release of fluid trapped within the body A between 40 the shoulders 17 and 24 when the sections are released for movement.

It is believed that the operation of the 45 jarring tool provided by the present invention will be readily apparent from the foregoing detailed description. Where the tool is employed within a well in connection with a fishing tool in engagement with a lost object or fish within the well, the tool and fishing tool are suspended or carried at the lower 50 end of an operating string such as a string of drill pipe, or the like. The parts of the jarring tool are normally in the positions illustrated in Fig. 1 of the drawings. When 55 it is desired to actuate the tool to impart a jarring action to the object engaged by

the fishing tool, an upward strain is put upon the section A through the operating string. The upward strain imparted to the section A acts through the members 50 of the means 11 and the carrier 31 to hold the latches 27 in tight compressive engagement with the shoulder 30. The members 50 are stretched or elongated by the strain imparted to the section A and yield to permit the section A to shift or move relative to the section B. Movement of the section A relative to the section B causes movement of the sleeve 40 relative to the section B and accordingly the latches 27. Upon a predetermined tensile strain being exerted on the section A while the section B is held stationary the members 50 yield a certain amount to permit the section A to shift a given distance relative to the section B so that the sleeve 40 is shifted 60 out of engagement with the upper ends of the latches 27. Upon the release of the sleeve 40 from the latches 27 the compression strain on the latches causes the latches to operate off the shoulder 30 to suddenly release the sections A and B for relative longitudinal movement. Upon releasing of the latches 27 the shoulder 17 on the section A is brought into hammering or jarring engagement with the shoulder 24 on the section B.

After actuation of the tool the strain is no longer on the members 50 and they assume their normal proportions. The section A may be shifted relative to the section B to bring the latches 27 in position where the springs 44 urge them into cooperative engagement with the shoulder 30. The sleeve 40 being freely slidably within the part 12, automatically returns to its position where it retains the latches 27 in cooperative engagement with the shoulder 30.

Having described only a typical preferred form of my invention, I do not wish to limit myself to the specific details set forth, but wish to reserve to myself any changes or variations that may appear to those skilled in the art or fall within the scope of the following claims.

Having described my invention, I claim:

1. A well tool including, two sections related for limited relative longitudinal movement, releasable latch means holding the sections against relative movement, and means for controlling the release of the latch means, including a part yieldable under tension associated with the latch means and connected 100 to one section.

2. A well tool including, two sections related for limited relative longitudinal movement, a latch to releasably hold the sections against relative movement, and means for releasing the latch upon a predetermined strain being exerted on the sections, including an extensible member connecting the latch and one section.

3. A well tool including, two sections re-

lated for limited relative longitudinal movement, a latch to releasably hold the sections against relative movement, and means for releasing the latch upon a predetermined strain being exerted on the sections, including a 5 cable connecting the latch and one section.

4. A well tool including, two sections related for limited relative longitudinal movement, a pivoted latch to releasably hold the 10 sections against relative movement, and means for releasing the latch upon a predetermined strain being exerted on the sections, including an extensible member connecting the latch and one section.

5. A well tool including, two sections related for limited relative longitudinal movement, a latch to releasably hold the sections against relative movement, and means for releasing the latch upon a predetermined strain being exerted on the sections, including a 15 extensible resilient member connecting the latch with one section.

6. A well tool of the character described including, two sections related for limited 25 relative longitudinal movement, a projecting part on one section, a latch adapted to engage the said part to releasably hold the sections against relative longitudinal movement, and means for causing the latch to release upon a predetermined strain being exerted on the 30 sections, including a member connecting the latch and the other section and operable upon a tensile strain applied to it to cause the release of the latch.

35. 7. A well tool of the character described including, two sections related for limited relative longitudinal movement, a projecting part on one section, a shiftably mounted latch adapted to engage the said part to releasably hold the sections against relative 40 longitudinal movement, and means for causing the latch to release upon a predetermined strain being exerted on the sections, including a member connecting the latch and the 45 other section and operable upon a tensile strain applied to it to cause the release of the latch.

8. A well tool of the character described including, two sections related for limited 50 relative longitudinal movement, a projecting part on one section, a pivoted shiftably mounted latch adapted to engage the said part to releasably hold the sections against relative longitudinal movement, and means 55 for causing the latch to release upon a predetermined strain being exerted on the sections, including a member connecting the latch and the other section and operably upon a tensile strain applied to it to cause the release of the latch.

9. A well tool of the character described including, two sections related for limited relative longitudinal movement, a projecting part on one section, a latch adapted to 65 engage the said part to releasably hold the

sections against relative longitudinal movement, means on the other section normally retaining the latch in engagement with the part, and means for causing the latch to release upon a predetermined strain being exerted on the sections, including a member connecting the latch and the other section and operable upon a tensile strain applied to it to cause the release of the latch. 70

10. A well tool of the character described including, two sections related for limited relative longitudinal movement, a projecting part on one section, a latch adapted to engage the said part to releasably hold the sections against relative longitudinal movement, a 75 sleeve loosely connected with the other section normally retaining the latch in engagement with the part, and means for causing the latch to release upon a predetermined strain being exerted on the sections, including a member connecting the latch and the other section and operable upon a tensile strain applied to it to cause the release of the latch. 80

11. A well tool including, two sections related for limited longitudinal movement, one section being tubular, the other section extending into the tubular section, a latch shiftably mounted in the tubular member operable to releasably hold the sections against relative longitudinal movement, and a cable attached to one section and connected with the latch and operable through elongation upon a predetermined strain being exerted on the section to cause the latch to release. 95

12. A well tool including, two sections related for limited longitudinal movement, one section being tubular, the other section extending into the tubular section, a latch shiftably mounted in the tubular member operable to releasably hold the sections against relative longitudinal movement, and means whereby the latch is released upon a predetermined strain being applied to the sections including a plurality of cables attached to one section and connected with the latch. 100 105

13. A well tool of the character described including, two sections related for relative longitudinal movement, one section being tubular, the other section extending into the tubular section, a shoulder on one section, a carrier shiftably mounted in the tubular section, latches on the carrier adapted to engage the shoulder to releasably hold the sections against movement and means whereby the latches are released upon a predetermined strain being applied to the sections, including an extensible resilient member connecting the carrier with one of the sections. 115 120

14. A well tool of the character described including, two sections related for relative longitudinal movement, one section being tubular, the other section extending into the tubular section, a shoulder on one section, a carrier shiftably mounted in the tubular sec- 125 130

tion, latches on the carrier adapted to engage the shoulder to releasably hold the sections against movement, means normally holding the latches in engagement with the shoulder, and means whereby the latches are released upon a predetermined strain being applied to the sections, including an extensible resilient member connecting the carrier with one of the sections.

15. A well tool of the character described including, two sections related for relative longitudinal movement, one section being tubular, the other section extending into the tubular section, a shoulder on one section, a carrier shiftably mounted in the tubular section, latches on the carrier adapted to engage the shoulder to releasably hold the sections against movement and means whereby the latches are released upon a predetermined strain being applied to the sections, including an extensible resilient member connecting the carrier with one of the sections, there being a fluid passage through the sections.

16. A well tool of the character described including, two sections related for relative longitudinal movement, one section being tubular, the other section extending into the tubular section, a shoulder on one section, a carrier shiftably mounted in the tubular section, latches pivotally supported on the carrier adapted to engage the shoulder to releasably hold the sections against movement, and means whereby the latches are released upon a predetermined strain being applied to the sections, including an extensible resilient member connecting the carrier with one of the sections.

17. A well tool of the character described including, two sections related for relative longitudinal movement, one section being tubular, the other section extending into the tubular section, a shoulder on one section, a carrier shiftably mounted in the tubular section, latches on the carrier adapted to engage the shoulder to act under compression to releasably hold the sections against movement, and means whereby the latches are released upon a predetermined strain being applied to the sections, including an extensible resilient member connecting the carrier with one of the sections.

In witness that I claim the foregoing I have hereunto subscribed my name this 10th day of March, 1930.

IRA J. McCULLOUGH.
